UNITED STATES PATENT OFFICE.

CHARLES E. ROBERTS, OF CHICAGO, ILLINOIS.

MACHINE FOR SPLITTING LEATHER SCRAP.

SPECIFICATION forming part of Letters Patent No. 372,640, dated November 1, 1887.

Application filed April 5, 1886. Serial No. 197,825. (No model.)

To all whom it may concern:

Be it known that I, CHARLES E. ROBERTS, a citizen of the United States, residing in Chicago, in the county of Cook and State of Illinois, have invented a new and useful Improvement in Machines for Splitting Leather Scrap, of which the following is a specification.

My invention relates to machines for utilizing small pieces or scraps of leather by splitting the same in such way as to leave a narrow margin or hinge at one edge, uniting the two split parts together, and thus forming, when opened out, a piece of leather of almost double the area of the original scrap. In machines of this kind it is desirable to automatically adjust the splitting knife accurately between the feed-rollers by which the scrap is forced against the knife, either by separating or moving both the feed rollers laterally, where the knife is fixed on the stationary frame of the machine, or else by moving or adjusting the knife at the middle point between the feed-rollers by the lateral movement of the movable feed-roller, where one of the feed-rollers is stationary or journaled in fixed bearings on the frame of the machine. Heretofore the two feed-rollers, whether one or both of them has been mounted in movable bearings, have usually been geared together, the rollers being separated by the scrap or piece of leather as it passes between them against the action of springs which tend to force the feed-rollers together. The intermeshing gears on the feed-rollers, however, tend to force the feed-rollers apart independent of the scrap, and the greater the resistance offered by the knife or scrap to the revolution of the feed-rollers the greater is the tendency of the intermeshing driving-gears to separate the feed-rollers; and as it has been customary and usually necessary to have driving-gears only upon one end of the shafts, this evil is greatly aggravated, because these driving-gears will thus tend to separate the rollers only at one end, and thus unequally. To obviate this difficulty in the practical operation of such machines, one feature of my invention consists in driving the rolls by gears or shafts journaled in fixed bearings, the rotary movement of these gears or shafts being communicated to the feed-rollers, one or both, according as one or both are movable, by a universal or knuckle joint connection, so as to permit

the free lateral movement of the roller or rollers, and at the same time prevent the intermeshing gears from having any tendency to 55 separate the rollers or to press them together.

Another feature of my invention consists in so combining the edge-straightening knife and splitting-knife in operative position about the periphery of one and the same feed-roller 60 that only two feed-rollers will be required to force the scrap by and against both the edge-straightening knife and the splitting-knife, and leave the requisite hinge or uncut margin at the straightened edge of the scrap. 65 This I do by mounting the edge-straightening knife at the end of the splitting-knife, with the requisite space between to leave the hinge or uncut margin at the straightened edge of the scrap, the cutting edge of the edge-straightening knife being preferably almost on a level or line with the cutting-edge of the splitting-knife. By this means I not only greatly simplify and cheapen the construction and operation of the machine—one or more feed-rollers 70 being entirely dispensed with—but materially increase its efficiency and accuracy of operation, and render it possible to leave a uniform hinge or uncut margin of any desired thickness. 75

Another feature of my invention consists, in connection with the splitting-knife, of a pair of flattening or spreading rollers mounted below, and one on each side of the end of the splitting-knife, so as to spread and flatten the 85 two leaves or split parts of the scrap as the same passes down over the splitting-knife.

Other features of my invention consist in the novel devices and novel combinations of devices, hereinafter more particularly pointed out in the claims.

In the accompanying drawings, which form a part of this specification, and in which similar letters of reference indicate like parts, Figure 1 is a front elevation of a machine embodying my 95 invention. Fig. 2 is a plan view of the same. Fig. 3 is an end view. Figs. 4, 5, and 6 are sections on lines 4 4, 5 5, and 6 6 of Fig. 1. Fig. 7 is an enlarged view showing the end of the splitting-knife. Fig. 8 is a section on line 100 8 8 of Fig. 7. Fig. 9 is a horizontal section on line 9 9 of Fig. 1. Figs. 10 and 11 are detail views showing the means for securing the edge-straightening knife; and Fig. 12 shows the form

of grooving on the feed-rollers. In Figs. 1 and 9, for convenience, the grooving is not shown.

In the drawings, A represents the frame of the machine; B, the splitting-knife; C, the edge-straightening knife; and D and D', the feed-rollers, by which the scrap is forced against both said knives.

The splitting-knife B is mounted upon or secured to a laterally-moving slide or carriage, E, so that the position of the knife may be automatically adjusted at the middle point between the two feed-rollers by the movement of said slide. One of the feed-rollers, D, is stationary, or journaled in fixed boxes, on the frame of the machine, while the other, D', is movable and journaled in laterally-sliding boxes d, so that the roller D' may separate from the roller D, according to the thickness of the scrap fed between them. Each end of the roller D' is journaled in separate or independent boxes d, so that if the scrap happens to be thicker at one end than the other the separation or movement of the roller D' at each end may correspond thereto. The roller D' is pressed against the roller D by springs, F, operating against one end of levers F', which are pivoted at f to the frame of the machine. The upper end of these levers carries adjustable pins f', which bear against the movable boxes d of the roller D'. The knife carriage or slide E is connected to the levers F' at the middle point of said levers between the pivots f and the pins f', so that the knife will receive at each end just half the movement of the roller D', and thus always accurately adjust the knife at the middle point between said rollers, whatever may be the thickness of the scrap and consequent movement of the roller D'. The knife carriage or slide E is pivoted at each end upon sliding bars H H, which bars are connected by links h with said levers F'. As this means of mounting and adjusting the splitting-knife automatically by the movement of the movable feed-roller constitutes, in part, the subject of my previous application, No. 176,643, filed October 12, 1885, and does not form the subject of claim in this application, it is not deemed necessary to herein show and describe the same in detail; and for a more full description thereof reference is made to said previous application and the patent thereon to be granted.

The edge straightening knife C is mounted at one end of the splitting-knife B, with just space enough between said edge-straightening knife and the end of said splitting-knife to leave the required hinge or uncut margin at the straightened edge of the scrap. The frame A, or the bracket thereon, which supports the stationary roller D of the machine, is provided with a slot, a, in which said knife fits. The knife is secured in said slot by a plug, c, having a slot, c', to receive the edge-straightening knife C. This plug is tightened against the knife by means of a screw, c'', the collar c' on which bears against the frame A, and which enters a threaded hole in the plug

c, so that by tightening the screw the plug is caused to bind the knife. A screw, c', serves to hold the plug c from turning when the screw c'' is tightened.

The cutting-edge of the edge-straightening knife C is preferably arranged on about a line with or slightly below the cutting edge of the splitting-knife B. By this means I am enabled to dispense not only with one or more feed-rollers, but also with the gage plate or guide which heretofore has ordinarily been used in machines of this kind for the straightened edge of the scrap to abut against as the scrap is carried from the edge-straightening knife to the point where the splitting-knife has heretofore been located. As in my present improvement the two knives have their cutting-edges very near each other, there is no opportunity for the scrap to get out of proper relation or position in passing from one knife to the other, and no gage or guide plate is therefore necessary in order to preserve the proper hinge or uncut margin of the scrap.

The splitting-knife B is provided with an offset or notch, b, at its end, and at this notch a flattening or spreading roller, G, is mounted. This roller is preferably journaled on the knife carriage or slide to which the knife is secured, and this roller I prefer not to drive positively, except by friction or contact with its companion roller K. The periphery of this roller G should be just about on a line with the end of the splitting-knife B. The flattening-roller K is journaled on a swinging frame, K', which is preferably pivoted to the knife carriage or slide E, and this roller is pressed or forced against its companion roller G by a spring, k. The rollers G and K, and especially the roller G, may preferably be comparatively short in length, so that the split scrap, as it leaves the knife B, will more readily enter between said rollers. The rollers G and K will serve to open out the two leaves of the split scrap and press them out flat into a sheet, the two parts of which are united by the hinge or uncut margin.

d' d'' are intermeshing gears by which the rollers D and D' are driven. Both these gears, or the shafts to which they are secured, are mounted in fixed bearings on the frame of the machine. As the roller D, in the machine shown in the drawings is stationary or immovable, its driving gear d' may be secured directly to the shaft of this roller. The roller D', however, is movable to and from the roller D, and the motion of its driving gear d'' is communicated to it by a universal or knuckle joint connection, so as to permit of this lateral movement of the roller D'. This connection may preferably consist of a rod or shaft, d', having oval or curved ends d' d'', square or rectangular in cross-section, one of which ends, d', fits into a square recess, d'', in the end of the roller D' or its shaft, while the other fits in a similar recess, d'', in the hollow shaft or sleeve d' of the gear d''. The gear d'', or its shaft d'', has a journal or bearing, d', on the frame of

the machine. By making the faces of the square blocks d^4 d^5 on the ends of the rods d^3 slightly curved, as indicated in the drawings, the requisite lateral movement of the roller D' is permitted, while at the same time the square plugs d^4 d^5 at their middle points fit, though loosely, the square recesses in the shaft of the roller D' and of its driving shaft or gear, so that there will be little lost rotary movement.

10 While I deem this construction to be the best and cheapest, still any other suitable substitute or equivalent form of knuckle or universal joint connection between the roller D' and its driving gear or shaft may of course be used 15 without departing from my invention.

The knife carriage or slide E is adjustable endwise on its sliding bars H H , in order to regulate the thickness of the uncut margin or hinge, or the space between the end of the 20 splitting-knife and the edge-straightening knife; but as this constitutes no feature of the present improvement, and forms a part of the subject-matter of my previous application, it is not herein shown and described in detail.

25 L represents the fast pulley, and L' the loose pulley, by which the machine is operated. The fast pulley L is secured to the hollow shaft d^8 of the gear d^2 , and the loose pulley L' rotates upon a hub, l , of the pulley L .

30 The flattening-roller K is operated from the pulley L by means of a band, M , which passes over and around pulleys m , m' , m^2 , m^3 , m^4 , and m^5 , pulley m being on the shaft of said flattening-roller K .

35 It will of course be understood that where my improvement is used in a machine wherein both the feed-rollers are movable to and from each other, instead of only one of them movable, as in the machine shown in the drawings, 40 a similar universal or knuckle joint connection should be used between each of said feed-rollers and its operating gear or shaft.

The straightening-knife should be about one-sixteenth of an inch (more or less) from the 45 end of the splitting-knife; and as the two knives are combined together in such way that their cutting-edges are nearly on a line with or close to each other, the hinge or uncut margin may be made very narrow or thin and 50 perfectly regular, so that the two leaves or split parts of the scrap will easily open out; and by this means and for this reason I am enabled also to dispense with the spreading-block, with which this class of machines have 55 heretofore been provided, in order to open out the leaves of the split scrap. In my machine the hinge or uncut margin is left so even, narrow, and regular that the two leaves of the split scrap will almost open of their own ac-

60 cord. The flattening-rollers G and K serve not only to flatten out the leaves of the scrap, but also to help draw the scrap through the machine. The roller G is preferably mounted in anti-friction bearings, as indicated in the 65 drawings.

In practice I ordinarily make the gears d'

and the roller D all in one piece, the same having a central hole or opening, through which is inserted a non-rotary pin or shaft, d^{10} , which serves as a bearing for the gear and roller. This construction facilitates the mounting or securing of the edge-straightening knife C in place at the end of the feed-roller D .

70 The feed-rollers D and D' are furnished with spiral or inclined grooves D^2 . The grooves on the roller D' are inclined in the same direction as those on the roller D , so that the grooves will cross each other at the point of contact between the rollers, the rollers of course revolving together or in opposite directions. 75 By this means I find that the rollers have a better hold upon the leather fed between them, and that the same will be fed much more accurately and positively than if these grooves are made parallel to the axis of the rollers, as 80 has heretofore usually been done.

In my said previous application No. 179,643, I have shown, described, and claimed a leather-scrap splitting and spreading machine having an edge straightening knife and a splitting-knife and three feed-rollers, two of which—one fixed and the other movable—serve to feed the scrap against the splitting-knife, and wherein the splitting-knife is mounted upon a movable slide and connected with the movable feed- 90 roller by the same mechanism as herein shown and described, and wherein the split scrap is opened and spread by being passed between a spreading-block and a flattening-roller. I therefore do not herein claim such subject-matter, the same being claimed in said previous application, and I disclaim in this application everything which is claimed in said previous application, to which, and the patent thereon to be granted, reference is hereby made 95 for greater certainty.

I do not herein claim, broadly, the combination, in a leather-scrap-splitting machine, of the edge straightening knife and splitting-knife, both arranged about the periphery of one and the same feed-roller, as that, in part, forms the subject of my said previous application No. 179,643.

I claim—

1. The combination, with feed-rollers D and D' , of the edge-straightening knife C , mounted on the frame of the machine at the end of said feed-rollers, gear d' , said roller D and gear d' being cast in one piece and having a central opening and stationary shaft, d^6 , upon which 110 said roller D and gear d' are journaled, substantially as specified.

2. The combination, with a splitting-knife, of a fixed feed-roller, D , movable feed-roller D' , driving-gear d^2 , hollow shaft d^8 , and connecting-rod d^3 , substantially as specified.

3. The combination, with a splitting-knife, of feed-roller D , movable feed-roller D' , having recess d^6 in its end, driving-shaft d^8 , having recess d^7 , and connecting-rod d^3 , having angular 130 plugs or ends d^4 d^5 , substantially as specified.

4. The combination, with a splitting-knife,

of feed-roller D, movable feed-roller D', having recess d^* in its end, driving-shaft d^* , having recess d^* , and connecting-rod d^* , having angular plugs or ends $d^* d^*$, with curved faces, substantially as specified.

5. The combination, in a leather-scrap-splitting machine with a single pair of feed-rollers, of an edge-straightening knife and a splitting-knife, both arranged in operative position between said one and the same pair of feed-rollers, said edge-straightening knife being at the end of the splitting-knife, with a space between the same to leave an uncut margin or hinge uniting the two leaves or split parts of the scrap, substantially as specified.

6. The combination, in a leather-scrap-splitting machine with a pair of feed-rollers, of an edge-straightening knife and a splitting-knife, both arranged in operative position between said feed-rollers, said edge-straightening knife being at the end of the splitting-knife, with a space between the same to leave an uncut margin or hinge uniting the two leaves or split parts of the scrap, and flattening-rollers G and K, substantially as specified.

7. The combination, in a leather-scrap-splitting machine with a pair of feed-rollers, of an edge-straightening knife and a splitting-knife, both arranged in operative position between said feed-rollers, said edge-straightening knife being at the end of the splitting-knife, with a space between the same to leave an uncut margin or hinge uniting the leaves or split parts of the scrap, said splitting-knife having a notch

or recess, b, at its end, and flattening-roller G, mounted at such recess b, and flattening-roller K, substantially as specified.

8. The combination, with a splitting-knife and an edge-straightening knife, of a pair of feed-rollers, a driving-pulley mounted on a shaft parallel to said feed-rollers, mechanism for communicating motion from said driving-pulley to said feed-rollers, flattening-rollers G and K, journaled at right angles to said feed-rollers, a band, M, and pulleys for communicating motion from said driving-pulley L to said flattening-roller K, substantially as specified.

9. The combination, with splitting-knife B, having recess b at its end, of edge-straightening knife C, feed-rollers and flattening-roller G, mounted at said recess b in said knife, and a flattening-roller, K, substantially as specified.

10. The combination, with the frame or part A, having slot a, of knife C, fitting in said slot, plug e, having slot e', and screw e', substantially as specified.

11. The combination, with feed-rollers D and D', of edge-trimming knife C, mounted in the frame of the machine at the end of said feed-rollers, and non-rotary shaft or pin d^{10} , said roller D being hollow and mounted to revolve upon said shaft or pin d^{10} as a bearing or journal, substantially as specified.
